[57] CLAIM

The ornamental design for a gift package bow, as
shown.

DESCRIPTION

FIG. 1 is a perspective view of a gift package bow
showing my new design;

FIG. 2 is a top plan view thereof;

FIG. 3 is a front elevational view thereof;

FIG. 4 is a left side elevational view thereof, the right
side being a mirror image;

FIG. 5 is a rear elevational view thereof; and,

FIG. 6 is a bottom plan view thereof.

*FIG. 1**FIG. 2**FIG. 4*

FIG. 3

FIG. 5***FIG. 6***
